PAGE 2

FIG. 4

FIG. 1 is a perspective view of a combined packaging tray and cover, embodying my new design;

FIG. 2 is a top plan view thereof on an enlarged scale;

FIG. 3 is a section taken on line 3—3 of FIG. 2 on a slightly larger scale; and

FIG. 4 is a side elevation thereof, a portion being broken away for convenience of illustration.

I claim:

The ornamental design for a combined packaging tray and cover, substantially as shown and described.
